UNITED STATES PATENT OFFICE

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

DIAL-READING AXIAL ADJUSTMENT FOR SHAPER FEED

Application filed October 30, 1923. Serial No. 671,809.

Shaping machines have been so designed that the feed is adjustable through a hand-grasp mounted coaxially with an oscillating member having a box-like form of a more or less rectangular shape bearing graduations on its elongated front-face.

The aim of the present invention is to carry forward the advantageous characteristics of the aforesaid mechanism by a neater structural arrangement whereby the oscillatory motion of said member will be less conspicuous through a symmetrical form of a substantially circular shape.

It is also an object to effect an improvement in the means indicating the extent of feed by arranging the graduations in the form of a dial and by so proportioning the parts that a single revolution of the hand-grasp will accomplish the full extent of adjustment thereby avoiding the necessity of turning the hand-grasp more than a fractional revolution for all degrees of adjustment within the full extent of feed.

While by locating the hand-grasp concentrically with the axis of oscillation of the member on which it is mounted, it becomes much easier for the user to make the adjustment while the parts are in motion, it calls nevertheless for some dexterity in manipulation to set the adjustment precisely to any selected graduation of the scale and another object of this invention is to increase the facility with which that may be done by providing a detent so that the user may by a sense of feeling set the hand-grasp quickly and precisely to any desired graduation while the parts are in motion.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is a fragmentary side-elevation of a shaper embodying this improvement. Fig. 2 is a sectional detail through the timing mechanism. Fig. 3 is a vertical section through the hand-grasp and the parts combined therewith for adjusting the extent of feed. Fig. 4 is a side elevation, partly in section through line 4—4 of Fig. 3, showing further details especially of the detent mechanism, and Fig. 5 is a fragmentary horizontal section through line 5—5 of Fig. 3.

Referring to the drawings, there is shown pivotally mounted on the side of the shaper a housing consisting of a round casting or shell 100 having a circular cover 102. It may be noted, at this point, that the shell 100 has substantially all portions of its periphery approximately at the same radial distance from the axis of the shell thereby giving this member a wheel-like form with the advantage that, when it is rocked or oscillated about its axis, the motion is not conspicuous and its formation does not present any projections which, if moved to and fro in a circular path, would be likely to hit the user of the machine. It may furthermore be noted that this formation provides considerable room for the admission of a milling cutter during the process of manufacture in which it is necessary to cut the slideway 117. Also, by reason of the proportions given the shell 100, it is made possible to journal the adjusting screw 113 directly in the same; thereby making a more rigid and accurate arrangement than where such parts are journaled in a cover as in the case of the structure of the aforesaid application.

It will be understood that the hollow member aforesaid is rocked to and fro continually during the operation of the machine by means of the arm 23 operated synchronously with the ram 4 and that this intermittent motion is, in turn, utilized to feed the work-carrier 11 through a suitable mechanism A which need not be described in order to afford an understanding of this particular invention.

The motion to the mechanism A is transmitted through a link 42 in a manner described in my Patent #1,267,158 issued May 100

21, 1918; said link being journaled in this instance on a stud 116 which projects laterally from a nut 115 which rides on a screw 113 held against translation by a collar 114 at its upper end and a bevel gear 112 pinned to the screw. This bevel gear is comparatively small and meshes with a large diameter bevel gear 111 set closely to the nut and having its hub 110 journaled in a hole through the cover 102 centrally with the axis of oscillation of the parts. On the outer end of the hub 110 is affixed a hand-grasp 105 in the nature of a hand-wheel which, being circular in form, may also rock to and fro without making the oscillatory movement conspicuous.

It will be perceived that, by more or less rotating the hand-grasp 105 relative to the housing on which it is centrally journaled, that the screw will be rotated through the gearing and the nut fed radially an appropriate distance from the center of oscillation; the nut being preferably interfitted with a slideway 117 to maintain it in alignment. By reason of the fact that the driving gear 111 is considerably larger than the gear 112 on the screw, the screw will be rotated several times when the large gear 111 has been turned through one revolution; the ratio being such that the nut will be fed from its zero position to its maximum feeding rate position and since the hand-grasp 105 moves as a unit with the gear 111, a single revolution of the hand-grasp is all that is necessary to accomplish all of the feeding rates.

To enable the user accurately to observe the feed resulting from any position of the hand-grasp, the latter is provided with an annular part 106 on the periphery of which is cut a scale of graduations 107. The cover 102 also provides a marker or pointer 104 which indicates the extent to which the hand-grasp 105 has been turned during the process of adjustment, these features being all very conspicuously located.

Cooperating with the visual graduations aforesaid is a detent arrangement for enabling the user, through his sense of feeling, to turn the hand-grasp sufficiently to bring any one of the divisions of the scale of graduations 107 into coincidence with the marker 104. The cover 102 provides a hub 103 on the end-face of which is a series of shallow holes 109 and a spring-pressed detent 108 is arranged, as shown by Fig. 3, in the hub of the hand-grasp so that it may engage selectively any one of the aforesaid holes. The end of the detent 108 is sufficiently rounded so that, while it may easily be moved from one hole to another, it will serve to hold the hand-grasp 105 in any position into which it has been adjusted and thereby prevent creeping or other displacement of the hand-grasp relative to the hollow frame during the operation of the machine.

It will thus be perceived that this invention provides a very simple structural organization which admits of being readily manufactured and which when installed may be adjusted with great facility during the operation of the machine, and which will remain in its adjusted position, and which will be exceedingly neat and will not render conspicuous the oscillatory movement during the running of the machine.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention, and, therefore, such adaptations should be, and are intended to be, comprehended within the meaning and range of equivalency of the following claim.

Having thus revealed this invention, I claim as new and desire to secure the following combinations and elements, or equivalents thereof, by Letters Patent of the United States:

A variable throw device comprising a substantially circular housing having an open forward face and a shank extending from the rear face thereof for supporting said housing for oscillatory movement about its axis; a screw shaft mounted in said housing transversely of its axis; a nut including a crank pin mounted on said shaft, said crank pin being positioned between the shaft and the inner rear wall of said housing; guide means on said inner rear wall for slidably supporting said crank pin; a cover plate for said forward face; and manually operable means extending through said cover plate co-axial with said housing for rotating said screw shaft to adjust said crank pin.

In witness whereof, I hereunto subscribe my name.

WILLIAM F. ZIMMERMANN.
